UNITED STATES PATENT OFFICE.

BUDD D. BOHANON, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

TIP-MEASURING APPARATUS.

1,346,167.

Specification of Letters Patent. Patented July 13, 1920.

Application filed March 8, 1916. Serial No. 82,883.

To all whom it may concern:

Be it known that I, BUDD D. BOHANON, a citizen of the United States, residing at Boston, in the county of Suffolk and State 5 of Massachusetts, have invented certain Improvements in Tip-Measuring Apparatus, of which the following description, in connection with the accompanying drawings, is a specification, like reference characters on the 10 drawings indicating like parts in the several figures.

This invention relates to apparatus for use in the manufacture of shoes and particularly to tip measuring mechanism designed 15 for use in connection with the pulling-over operation as performed by pulling-over machines of the type shown in United States Letters Patent No. 1,029,387, granted June 11, 1912, on application of Ronald F. Mc- 20 Feely, and similar machines in which the top face of a shoe is visible to the operator during the pulling-over operation. As is well understood, one of the steps in the operation of pulling-over a shoe is the correct 25 positioning of the rear edge of the toe cap, commonly referred to as the tip line, longitudinally of the shoe in order that the length of the toe tips of a given size or style or of a given pair of shoes may be the same. 30 The requirements of the trade necessitate that the tip lengths of a pair of shoes be substantially identical and in order to secure this accuracy it is desirable to employ mechanical means for assisting the eye of 35 the operator in measuring the length of the toe cap during the pulling-over operation.

It is the general object of this invention to provide a tip measuring device for pulling-over machines which will be convenient 40 to use, which normally will be out of the operator's way and with which the tip length of one shoe may be accurately compared with the tip length of the next succeeding shoe placed on the machine or with which 45 the lengths of the tips of shoes of a given style or size may be compared with a given standard.

In accordance with features of the invention the tip measuring device is mounted 50 on a support which is arranged for movement relatively to the machine frame into and out of tip measuring relation to the shoe and has parts adapted to be set to indicate the tip length of a given shoe, which

setting may be maintained and the device 55 applied to the succeeding shoe so that the tip length of that shoe may be made to correspond with the setting of the device which indicates the tip length of the preceding shoe or a given standard length. 60

As shown herein the tip measuring device is mounted for movement about a fixed vertical axis, located upon the frame of the machine, for movement into and out of tip measuring position the device, preferably 65 being carried by an arm which extends rearwardly and is pivoted to a bracket at one side of and upon the frame of the machine for movement in a plane oblique to the plane of the sole. By this construction the 70 tip measuring device is readily movable out of operative position and may be returned to bring the tip measuring device into the identical position relatively to the next shoe which it had been made to assume by application to the preceding shoe before being 75 moved away.

Another feature of the invention consists in means for mounting the tip measuring device so that it may normally be remote from 80 the shoe in the direction of the length of the shoe and may be brought into tip measuring position relatively to the shoe by a right line movement substantially parallel with the shoe bottom. Preferably means for holding 85 or locking the device in tip measuring relation to the shoe is provided. As herein shown, the device is held normally away from the shoe by a spring, and a ratchet and pawl is provided to lock the device in tip 90 measuring position. By this construction the tip measuring device may be set to indicate the length of a given toe tip and that setting may be maintained for application of the device to a succeeding shoe to ascertain 95 what adjustments of that shoe upper are necessary to produce a length of tip substantially identical with that of the preceding shoe or to compare each shoe with a given standard length indicated by the setting of 100 the tip measuring device.

These and other features of the invention will appear more fully from the following description when read in connection with the accompanying drawing and will be 105 pointed out in the appended claims.

In the drawing,
Figure 1 is a side view of a pulling-over

machine equipped with tip measuring mechanism embodying this invention;

Fig. 2 is a perspective view of a part of the tip measuring mechanism in its operative position relatively to the shoe held in the grippers of the pulling-over machine;

Fig. 3 is a top view of a part of the tip measuring mechanism;

Fig. 4 is a sectional detail of the adjusting mechanism of the tip line engaging member; and

Fig. 5 is a detail view taken at right angles of Fig. 4.

Referring to the drawings, it will be briefly explained that the pulling-over machine comprises toe and side grippers 1 and 3 by which the upper is seized and pulled over the last which is rested against a shoe bottom abutment or sole rest 5. A forked heel rest 7 is mounted on a movable carrier by which the rest is yieldingly advanced from a retracted position into engagement with the heel end of the shoe after the grippers have tensioned the upper and hold the upper firmly against the sole rest. Since the toe and side grippers first draw the upper over the last and force it against the sole rest the position of all shoes in the machine, irrespectively of their size and length, is nearly the same. The usual upper adjusting mechanism is provided by which the tension of the toe gripper may be increased or diminished to vary the position of the tip seam as well as the means including the lever 9 for shifting the upper transversely of the last and for moving one of the side grippers forwardly and the other backwardly for straightening the tip seam if it does not occupy the desired angular relation to the median line of the last.

The tip measuring mechanism embodying this invention comprises an arm or support 2 mounted to turn about a pivot 4 on a bracket fixed to the machine frame at one side thereof, the axis of the pivot extending parallel with the longitudinal median plane of the shoe. The forward end of the arm 2 has a hole extending in a direction parallel with the shoe bottom as the shoe is held in the pulling-over machine, the shoe being positioned as is usual in machines of this kind with the upper down and the sole at an inclination of approximately 35° to the horizontal. In the hole in the end of the arm 2 a stem 6 is mounted for longitudinal movement and is upheld by a spring 8. A stop piece 10 is held in fixed relation to the lower end of the stem 6 by a set screw 12 and upwardly extending portions 14 on the stop piece 10 engage flattened surfaces of the arm 2 to hold the stem against rotation. Between the portions 14 and pivoted thereto by a pin 16 is a pawl 18 which engages ratchet teeth 20 formed on the arm 2. By this construction the stem 6 may be depressed against

the spring 8 and will be held in depressed position by the pawl 18 until released by the operator.

The upper end of the stem 6 is bifurcated to receive a curved arm 22 which is rigidly held therein by a bolt 24. The arm 22 is curved to bring its free end into proper position to the shoe when the tip measuring device is in operative position.

On the free end of the arm 22 is secured a toe engaging member 25 constituting a toe end abutment which is brought into engagement with the end of the toe by pressing downwardly the stem 6 and is held in toe engaging position by the pawl 18. On the member 25 is mounted a slider 26 in which is mounted for sliding movement a tip seam locating member or tip line indicator 28 which has an end graduated as shown to indicate different lengths of tips. The members 25 and 28 constitute the tip line indicating means or tip measuring device as referred to herein. For adjusting the member 28 for a wider range of lengths of tips than is provided for by these graduations the member 28 is arranged for adjustment in the slide 26 and is held in different positions of adjustment by a spring pin 30 which is arranged to engage any one of a series of staggered holes 32 in the member 28. This is effected by mounting the spring pin 30 in an arm 34 which is pivoted at 36 to the slider 26. A slot 38 is provided in the slider 26 so that the pin may be swung with the arm 34 into position to engage any one of the staggered holes 32, Fig. 5. If desired the arm and pin may be placed in an intermediate position in which the pin will rest on the member 28 between the lines of holes 32 and will hold the member frictionally in adjusted position. The normally fixed angular relation of the arms 2 and 22 may be varied by loosening the set screw 12 and turning them about the stem 6 as an axis. These arms constitute in effect an angle arm, the angle of which may be varied as described to permit presentation of the tip measuring device properly under different conditions of work.

In the use of the mechanism the shoe is placed in the pulling-over machine as shown in Fig. 1 and the machine passed through the first portion of its cycle to place the upper under tension. The arm 2 is swung in a horizontal plane about the vertical axis 4 to bring the member 25 over the end of the toe of the shoe. The arm 22 is then depressed in a direction parallel with the shoe bottom against the spring 8 until the member 25 engages the shoe, the member being locked and held in that position by the action of the pawl 18 on the teeth 20. The slide 26 is moved on the member 25 if necessary to bring the member 28 into proximity to the tip line. If the member 28 is too far for-

ward for a toe of the given height, its contact with the toe will push the slide 26 backwardly on the member 25. The member 28 is then adjusted by withdrawing the 5 pin 30 by its head 40 against a spring 42 to free the member 28 which is then moved in the direction of the length of the shoe to the proper position to indicate the right length for the shoe or a series of shoes. The 10 head 40 is then released and the arm 34 swung to one side or the other to engage the nearest one of the staggered openings 32 or the member 28 may be held yieldingly in adjusted position by frictional action of the 15 spring pin 30 as described. When the tip seam has been properly located the mechanism is swung to one side out of the way of the operator about the axis 4. The pulling-over operation is then completed and another shoe is placed in the machine and its 20 upper tensioned. The mechanism may now be swung back about the axis 4 into the identical position it occupied in the treatment of the previous shoe and the tip adjusted in the well-known manner to the 25 length of the tip of the shoe previously pulled over. In case the position of the second shoe in the machine is not quite the same as that of the first shoe the pawl 30 30 18 may be released and the member 25 brought into position over the toe and then depressed to contact with the toe. This, however, may be done without disturbing the relative positions of the parts 25, 28, 35 and the tip length indicated by the device will be the same as for the previous shoe.

Having fully described my invention, I claim as new and desire to secure by Letters

Patent of the United States:

40 1. In a pulling-over machine, means for 40 locating a shoe in the machine in predetermined position, an arm mounted on the machine frame at one lateral side of the pulling-over mechanism for movement about a 45 definite fixed axis extending parallel to the longitudinal median plane of the shoe, and located at a substantial distance from said plane, and a tip line indicating means carried by said arm and movable laterally of 50 the shoe into and out of tip measuring relation to the shoe by movement of the arm about said axis.

2. In a pulling-over machine, means for 55 locating a shoe in the machine in predetermined position, an arm mounted on the machine frame for swinging movement about an axis extending at a substantial acute angle to the plane of the shoe bottom and tip line indicating means mounted on 60 said arm to be swung into and out of tip measuring relation to the shoe by movement of the arm about said axis.

3. In a pulling-over machine, means for 65 positioning a shoe in predetermined relation to the pulling-over instrumentalities, a tip

measuring device comprising a toe end abutment and a tip line indicator member, means for mounting said device for rectilinear movement in the direction of the length of the shoe, yielding means for holding the 70 device away from the shoe, and self-acting means for locking said device in operative position when moved toward the shoe.

4. In a pulling-over machine, means for 75 positioning a shoe in predetermined relation to the pulling-over instrumentalities, a tip measuring device comprising a toe end abutment and a tip line engaging member, means constructed and arranged to provide for movement of the device in 80 a direction substantially parallel to the shoe sole to bring the toe end abutment into operative relation to the toe end of the shoe, and means constructed and arranged to provide for movement of the 85 device in a plane oblique to that of the shoe sole to carry the device out of the way of the shoe while the shoe is being removed from the machine and the next shoe is being positioned in the machine. 90

5. In a pulling-over machine, means for 95 pulling over a shoe upper including means for locating a shoe in predetermined position, a tip measuring device having relatively movable parts constructed and arranged to be set to indicate a given length of tip, a support fixed relatively to the machine, means for mounting the device on the support for movement in a predetermined plane extending transversely of the 100 length of the shoe into and out of measuring relation to the toe of a shoe in the machine.

6. In a machine of the class described, a 105 tip measuring device comprising a toe end abutment and a tip line indicator being normally fixed but adjustable relatively to each other, means for yieldingly holding the toe end abutment away from the toe, and a slide on which said device is mounted for movement longitudinally of the shoe to permit movement thereof manually into engagement with the toe to bring the tip line indicator into measuring relation to the tip line, and means by which the device is 110 mounted to swing in a plane oblique to the general plane of the shoe bottom to permit movement of the device bodily away from the shoe after use and return of the device into the same position for comparison with 115 a succeeding shoe.

7. In a tip measuring device, a toe end abutment, a tip line indicating member mounted for sliding movement relatively to the toe end abutment in two directions 120 at right angles to each other, and means for frictionally holding the tip line indicating member in adjusted position relatively to the toe end abutment.

8. In a pulling-over machine constructed 130

and arranged to hold the shoe top down with the sole lengthwise at an angle of substantially 35° to the horizontal, a tip measuring device comprising a toe end abutment 5 and a tip line indicator, said device being mounted for movement in a horizontal plane toward and away from the shoe.

9. In a pulling-over machine constructed and arranged to hold a shoe top down with 10 the sole lengthwise at an angle of substantially 35° to the horizontal, a tip measuring device comprising a toe end abutment, and a tip line indicator, said device being mounted for rectilinear movement in a direction substantially parallel to the shoe 15 bottom and for movement in a horizontal plane.

10. Apparatus of the class described having, in combination, an arm having one end 20 pivoted on an axis located at one side of the machine, and extending at an acute angle to the bottom of the shoe in the machine, and tip measuring means mounted on the other end of the arm and adapted to be brought into and out of tip measuring 25 relation to a shoe by movement of the arm about said axis.

11. Apparatus of the class described having, in combination, a two-part angle arm 30 having its parts connected for relative adjustment to vary the angular relation of the parts of the arm, a pivot for one end of the arm to insure movement of the arm in a predetermined plane, tip measuring 35 means mounted on the other end of the arm

to be brought into operative relation to a shoe held in the machine by the movement of the arm about its pivot.

12. In a tip measuring device, a toe end abutment part, a tip line indicator part, a 40 member connecting said parts through which member one of said parts is arranged to slide, an arm pivoted to the member, and a spring pin on the arm arranged to pass through said member to engage a series of 45 staggered holes in the other part whereby the parts are relatively adjustable.

13. In a tip measuring device, a toe end abutment and a tip line indicator arranged to slide substantially at right angles to the 50 toe engaging face of the toe abutment, and means constructed and arranged to hold the tip line indicator frictionally in adjusted position relatively to the toe end abutment.

14. In a machine of the class described, a tip measuring device comprising a toe end abutment and a tip line indicator which are normally fixed but adjustable relatively to each other, a slide constructed and arranged for movement longitudinally of the shoe on which slide said device is carried to permit movement thereof manually into measuring relation to the shoe toe, and yielding means for normally holding the 60 slide away from the shoe.

In testimony whereof I have signed my name this specification.

BUDD D. BOHANON.
